UNITED STATES PATENT OFFICE.

CHARLES TRANSUE, OF MOUNT JEWETT, PENNSYLVANIA.

PRESSURE-RETAINING VALVE.

Application filed January 5, 1927. Serial No. 159,147.

This invention relates to an improved pressure retaining valve such as is used upon railway conveyances in association with air brake systems of conventional form.

5 The pressure retaining valve, as is well known to those familiar with devices of this kind, is used on grades when it is necessary to hold the brakes applied, while recharging auxiliary reservoirs or to hold the slack of 10 the train when approaching points where stops are about to be made.

For the convenience of trainmen, this valve is placed on the end of the car near the 15 brake wheel. It is connected by a small pipe with the exhaust port of the triple valve through which the air is exhausted from the brake cylinder when the brakes are released.

The present retaining valves for this purpose are provided with manually rotated valve plugs and require the trainmen to go from end to end of the train to see that the valves are in proper position according to the circumstances. Obviously, this is inconvenient and sometimes is not altogether successful, because careless train men at times either open the valve too much or too little.

What I propose to do, is to substitute a novel pressure retaining valve which includes the usual manually controlled means but in addition, is provided with an automatic spring open valve which may, under the action of a pressure from the system, be caused to close by the engineer in the cab.

35 The structural details and features of advantage of this improved arrangement will become apparent from the following description and drawings.

In the accompanying drawings forming a 40 part of this application, and in which like numerals are employed to designate like parts throughout the same:—

Figure 1 is a side elevation of a retaining valve constructed in accordance with the 45 present invention.

Fig. 2 is a central vertical section through the same.

Fig. 3 is a fragmentary sectional view in section and elevation showing the rotary 50 plug valve, and

Fig. 4 is a horizontal sectional view of portions shown in elevation, showing the relation of the two separate valves.

Referring to the drawings in detail, it 55 will be seen that the valve as an entirety, is designated by the reference character 1, the

same being composed of upper and lower half sections 2 and 3 respectively. The lower section 3 is formed with a screw threaded neck 4 at its upper end and also 60 with a cylindrical socket 5 at this end. Then too, it is formed with an internally screw threaded reduced connection 6 at its bottom with which the pipe 7, from an air control in the cab, is connected. 65

The pipe communicates with the socket thru the medium of the bore 8. Connected to the screw threaded part 4 is the upper half section 2 which is formed with an air passage 9 connected with a reduced air port 10 in the top of this part 2. This port is connected with the triple valve by means which is not shown. The upper end of the part is reduced and formed with a wrench engaging portion 11. Arranged in the 75 socket 5 is a cylindrical pressure operated valve 12 having a reduced extension 13 at its top extending into the passage 9. A coiled valve opening spring 14 surrounds this extension and bears upon the part 12. 80

Formed on one side of the passage 9 is a bypass 15 communicating with an air escape port 16 in the rotary plug valve 17, carried by the upper half section of the body. Relatively small ports 18 are connected with the port 16 and serve to slowly bleed the air in a well known manner. As is usual, this valve 17 is formed with a handle 19 by means of which it is moved to the various positions. Moreover, the body is formed on one side with an opening 20 with which the ports in the rotary plug valve are adapted to register. When the handle 19 is in a substantially horizontal position, the small port 18 registers with this opening 20 and 90 allows the air to bleed out slowly. 95

By moving the handle to vertical position however, the large port comes into play to permit the air to discharge freely. The operation of the manually actuated valve is well known and need not be extensively explained here. The improvement, however, as I have before stated is the provision of the additional spring opened but pressure closed sliding valve 12 carrying the reduced stem 13 having the pointed end cooperating with the valve seat formed at the juncture of the air passages 9 and 10. 100 105

In practice, a pipe not shown is connected with the port 10 and with the usual retaining valve port in the triple valve. Then the pipe 7 is extended to a pipe in the 110

respective car and all of the individual car pipes are coupled together and in turn connected with a control valve in the engineer's cab. These pipes serve to convey pressure 5 from the system and at his discretion, the engineer opens the valve in the cab to allow the pressure to flow through the system of pipes for lifting the slide valve 12 upwardly to closed position against the action of the 10 spring 14. Thus, the engineer can close all of the retaining valves whenever desired.

As soon as the pressure is released, the spring returns the valve to open position again.

15 No doubt, by considering the description in connection with the drawings, persons familiar with devices of this class will be able to obtain a clear understanding of the same. Therefore, a more lengthy description is thought unnecessary.

Minor changes coming within the field of invention claimed may be resorted to if desired.

Having thus described my invention, what 25 I claim as new is:—

1. A pressure retaining valve of the class described comprising a body composed of upper and lower detachably connected sections formed with a passage extending entirely therethrough, a reciprocatory valve 30 located in said passage for closing one end of the passage, a spring for normally moving said valve to one position, the valve being adapted to be moved to its other position under the action of the air pressure, and a rotary ported manually actuated valve carried by said body and cooperative with said air passage.

2. A pressure retaining valve of the class described comprising a body formed with an air passage, spring opened pressure closed valve in said passage, a pressure supply pipe connected with one end of the passage, the open end of the passage being adapted to accommodate a triple valve pipe, and a 40 manually actuated valve mounted in said body and in communication with said passage.

In testimony whereof I affix my signature.
